Burrow & Munro.

UNITED STATES PATENT OFFICE.

FRANK SOLEY, OF PHILADELPHIA, PENNSYLVANIA, ASSIGNOR TO THE MILLER LOCK COMPANY, OF PHILADELPHIA, PENNSYLVANIA, A CORPORATION OF PENNSYLVANIA.

LATCH.

Application filed July 21, 1922. Serial No. 576,520.

To all whom it may concern:

Be it known that I, FRANK SOLEY, a citizen of the United States, residing in Philadelphia, Pennsylvania, have invented certain Improvements in Latches, of which the following is a specification.

My invention relates to certain improvements in night latches of the type in which the bolt can be projected to such an extent as 10 to prevent a tool being passed between the bolt and the keeper. This type of latch is known as a "double throw latch."

The object of the invention is to improve the construction of a latch of this type and 15 to provide a positive means for holding the bolt when fully projected so that it cannot be pushed back without the use of a knob or a key.

The invention also relates to details of 20 construction of the means for releasing the bolt to enable it to be projected to its full extent.

In the accompanying drawings:

Fig. 1 is a view of my improved night 25 latch with the cover plate removed;

Fig. 2 is an end view of the latch;

Fig. 3 is a sectional view on the line 3—3, Fig. 1;

Fig. 4 is a view, similar to Fig. 1, showing the bolt projected to its full extent and locked;

Fig. 5 is a detached perspective view of the bolt;

Fig. 6 is a detached perspective view of 35 the locking block for the bolt;

Fig. 7 is a perspective view of the sliding release plate;

Fig. 8 is a detached perspective view of 40 the locking lever for holding the plate in the normal position; and

Fig. 9 is a detached perspective view of the pivoted arm for holding the bolt in the retracted position.

Referring to the drawings, 1 is the casing 45 of the lock. 2 is the cap plate having a tongue 3, which extends under a flange 4 of the casing and has bent portions 5, which are secured to the front wall of the casing by screw bolts 6. Mounted on this cap plate is 50 the key hub 7 having an arm 8, Fig. 3, which is shown by dot and dash lines in Fig. 1. This arm is arranged to come in contact with a pin 9 on an arm 10 on the spindle 11

of the knob 12. The spindle is mounted in 55 the casing 1 of the lock.

13 is a bolt, which extends throughout the length of the lock and passes through an opening in the forward end and through a guide opening at the rear end. In the bolt is an angular slot 14 through which extends 60 the pin 9 so that, on turning the key, or the knob, the bolt can be retracted. On the hub of the arm 10 are gear teeth 15, which mesh with the teeth of a rack 16 that forms part of the locking block 17. This locking block 65 has a portion 18, which rests back of a shoulder 19 on the bolt when the bolt is projected to its full extent. The rear of the block rests against the rear of the casing so that, when the bolt and the locking block are 70 in the position shown in Fig. 4, it is impossible to move the bolt as the block forms a positive stop therefor.

20 is a coiled spring mounted on a stud 20^a projecting from the casing. The stud and 75 spring extend into an opening 21 in the locking block, as shown in Figs. 1 and 6. The spring not only actuates the locking block, but also acts through the locking block, the geared hub 10, and pin 9, to project the bolt. 80

Located at one side of the bolt is a sliding release plate 22. The forward movement of this release plate is limited by the keeper, as the bolt is so proportioned in respect to the opening in the keeper that the plate will 85 strike the edge of the keeper and will be held while the bolt is further projected. The plate is slotted at 23 and extending into the slot is a pin 24 on the bolt 13. The slot 14 in the bolt is formed, as shown, so as to allow the pin to move a given distance in one direction after projecting the bolt to allow the block 17 to assume a position back of the bolt. When it is wished to withdraw the bolt, the pin is allowed to travel 90 a given distance in the slot to allow the block to move clear of the bolt before the pin acts to retract the bolt.

The above construction allows the bolt to 100 retract the plate when it is operated by the key, or the knob, and also allows the bolt to be projected to its full extent while the plate is held back by the keeper. The sliding plate has an offset slot 25 through which extends a pin 26 on a locking lever 27, loosely pivoted at 28. This locking lever has a lat-

eral projection 29, which extends over the bolt 13. The bolt is cut away at 30 to receive the portion of the locking lever and is undercut at 31 to prevent the lifting of the locking lever when the bolt is first retracted.

When the bolt is withdrawn, the plate 22 is withdrawn with it, and, as the plate is retracted, it lifts the lever 27. As the plate is held in the retracted position by the keeper, the bolt is allowed to move to its full extent, as shown in Fig. 4.

32 is a spring coiled around a stud 33. This spring bears against a lug 34 on the plate 22 so that, when the plate is released, it is projected by this spring. In order to lock the bolt in the full retracted position, an arm 35 is provided, which is adapted to enter a notch 36 in the bolt. This arm is mounted on a spindle 28, which forms the pivot for the lever 27. This spindle extends through the casing 1 and has an arm 37. This arm can be moved so as to raise, or depress, the arm 35. When the bolt is retracted and the arm 35 is depressed, it enters the notch 36 in the bolt and holds the bolt in the full retracted position.

By the construction hereinbefore described, it will be seen that the bolt can be held in the retracted position by the arm 35. When the bolt is released, it is returned to its normal position, as shown in Figs. 1 and 2. The sliding plate is carried with the bolt.

When a door, to which the lock is attached, is closed, the bolt is retracted by coming in contact with the keeper and it carries the sliding plate 22 with it. As soon as the bolt passes the edge of the keeper, it is projected, but the sliding plate is held by the keeper. The sliding plate also holds the lever 27 clear of the bolt 13, allowing the bolt to be projected to its full extent—or double throw position—as shown in Fig. 4. When, in this position, the locking block 17 is moved back of the shoulder 19 so that it forms a positive lock for the bolt, which can only be retracted by the use of a key, or by turning the knob.

I claim:

1. The combination of a casing; a bolt mounted therein; an arm; a locking block geared thereto and arranged to be located back of the bolt when the bolt is in a fully projected position, said arm retracting the bolt and operating the locking block.

2. The combination of a casing; a slotted, sliding bolt mounted therein; an arm having a pin extending into the slot by which the bolt is retracted; and a locking block having an extension adapted to rest back of the bolt when said bolt is fully projected.

3. The combination of a casing; a slotted, sliding bolt mounted therein; an arm having a pin extending into the slot by which the bolt is retracted; a locking block having an extension adapted to rest back of the bolt

when said bolt is fully projected; and a spring tending to hold the block yieldingly in its projected position.

4. The combination of a casing; a bolt mounted therein, said bolt having an angular slot, the front wall of the slot being curved; an operating arm having a pin adapted to the slot; and a locking block geared to the arm so that the pin will have lost motion to allow the block to assume a position back of the bolt when the bolt is projected.

5. The combination of a casing; a bolt mounted therein; an arm for retracting the bolt, said arm having teeth; and a sliding block having a rack meshing with the teeth of the arm, said locking block having a portion arranged to be located back of the bolt when the bolt is fully projected.

6. The combination of a casing; a sliding bolt mounted therein, said bolt being slotted; an arm having a pin extending into the slot and by which the bolt is retracted, said arm having teeth; a locking block having a rack meshing with the teeth, the bolt having a shoulder and the block having a portion adapted to rest back of the shoulder when the bolt is fully extended; and a spring tending to hold the block yieldingly in its projected position.

7. The combination of a casing; a sliding bolt mounted therein; means for operating the bolt; means for locking the bolt in its full projected position; a sliding plate at the side of the bolt, said plate having a slot; a pin on the bolt extending into the slot and so arranged that the plate will be retracted by the bolt; an angular slot in the plate; a lever arranged to engage the bolt and having a pin extending into the slot, said lever holding the bolt in its normal position; and a spring for projecting the bolt.

8. The combination of a casing; a bolt slidably mounted in the casing; means for retracting the bolt; a block for locking the bolt in its full projected position; a sliding plate at the side of the bolt, said plate having a slot and pin connection with the bolt so that it is retracted with the bolt, the bolt being free to be projected independently of the plate; and a lever pivoted to the casing and actuated by the sliding plate, the bolt having an undercut portion and the lever having an extension arranged to be projected into the undercut portion when the bolt is in its normal position.

9. The combination of a casing; a sliding bolt mounted therein; an arm having a pin for actuating the bolt, said arm having a series of teeth; a locking block having a rack meshing with the teeth of the arm; a spring for projecting the bolt; means for holding the bolt in its normal position; and means for releasing the bolt so that it can be projected to its full extended position.

10. The combination of a casing; a bolt slidably mounted therein, said bolt being slotted; an arm having a pin extending into the slot, said pin actuating the bolt; a locking block geared to the arm; a spring pressing against the block; a sliding plate connected to the bolt; a lever actuated by the plate, said lever being arranged to hold the bolt in its normal position, the locking block holding the bolt in its full extended position, the bolt being notched; an arm arranged to enter the notch and to hold the bolt in its retracted position, said arm being mounted on a spindle extending through the casing; and an operating arm on the 15 spindle for moving the locking arm into and out of position.

FRANK SOLEY.
